UNITED STATES PATENT OFFICE.

EDWARD GREEN, OF HAMILTON, WASHINGTON.

NECKTIE-FRAME.

No. 895,629.

Specification of Letters Patent.

Patented Aug. 11, 1908.

Application filed December 4, 1907. Serial No. 405,091.

To all whom it may concern:

Be it known that I, EDWARD GREEN, citizen of the United States, residing at Hamilton, in the county of Skagit and State of 5 Washington, have invented certain new and useful Improvements in Necktie-Frames, of which the following is a specification.

The object of this invention is a necktie frame, which can be readily secured in position on a collar without adjustment before 10 a looking glass, which can be quickly removed from position, and from which the attached necktie can be easily removed to be cleaned or to be replaced by a new tie.

15 With this and other objects in view as will more fully appear as the description proceeds the invention consists in certain constructions and arrangements of parts as I shall hereinafter fully describe and claim.

20 For a full understanding of the invention and the merits thereof, reference is to be had to the following description and accompanying drawings, in which:

Figure 1 is a front view of a necktie showing 25 my improved frame, in dotted lines, applied thereto. Fig. 2 is a rear perspective view of the frame showing the necktie in dotted lines. Fig. 3 is a vertical section thereof. Fig. 4 is a horizontal section on the line x—x 30 of Fig. 3, and Fig. 5 is a front elevation of the frame.

Corresponding and like parts are referred 35 to in the following description and indicated in all the views of the drawing by the same reference characters.

My improved necktie frame is preferably constructed of such metal as tin and comprises an outer plate 1, which is designed to be covered by a part of the necktie to imitate 40 the knot of a "four-in-hand," the rest of the tie hanging downwardly from the plate 1 and constituting the loose ends of the said "four-in-hand." This plate 1 which preferably has a convex outer surface, tapers 45 toward its lower end as shown and is formed at its sides with flanges 2 which are doubled inwardly upon the said plate and are spaced therefrom, said plate being formed at its upper end with two upward pointed prongs 3.

An inner plate 4 which is correspondingly 50 tapered, is designed to be pushed downwardly between the plate 1 and the flanges 2 thereof and to be held by the latter in a position contiguous to said plate 1. The prongs 3 are adapted to be doubled inwardly upon 55 themselves to prevent the withdrawal of the inner plate 4. This plate 4 is formed with an opening 5 extending therethrough and a slot 6 communicating therewith and extending upwardly therefrom. 60

In the practical use of my improved necktie frame, the outer surface of the plate 1 is covered by a portion of the cloth, which then extends around the sides and the upper end of said plate and across the inner surface 65 thereof, the prongs 3 engaging the cloth passing around the upper end of the plate, as best shown in Fig. 3, to prevent the cloth from slipping. The inner plate 4 is pushed into position and the prongs are bent to prevent 70 its withdrawal, said inner plate serving to hold the cloth on the frame to imitate the knot of a "four-in-hand," the cloth hanging downwardly to form the loose ends. To attach the necktie to a collar, the frame is applied to the collar button so that the head of 75 the latter is received in the opening 5, said frame being then pulled downwardly until the head protrudes through the slot 6.

Having thus described the invention, what 80 I claim is:

The herein-described necktie frame comprising an outer plate tapered toward its lower end and formed at its upper end with a pointed prong, flanges formed on the sides of 85 the outer plate and doubled inwardly thereupon, and a correspondingly tapered inner plate mounted between the flanges and the outer plate, the prong being arranged to engage the cloth and being designed to be 90 doubled inwardly upon the plate, as and for the purpose set forth.

In testimony whereof I affix my signature in presence of two witnesses.

EDWARD GREEN. [L. s.]
